ROLL STORAGE MEANS

Egon R. Hoenle, Two Rivers, Wis., assignor to Hamilton Manufacturing Company, Two Rivers, Wis., a corporation of Wisconsin

Filed May 15, 1961, Ser. No. 110,039
11 Claims. (Cl. 312—319)

This invention relates to improvements in storage devices or files for rolls of drawings or other elongated cylindrical articles.

A roll file unit of the type involved in the present invention comprises generally a rectangular frame or housing containing a plurality of elongated tubular compartments accessible from the front of the unit for inserting or removing rolled articles such as drawings, plans, blueprints, tracings, etc. A door is preferably provided at the front of the unit, and usually the units are of modular design so that a plurality of units may be stacked or otherwise connected to form a unitary cabinet.

One object of the present invention is to provide a novel and improved door mounting arrangement for a roll file unit of the aforementioned type.

Another object of the invention is to provide, in a roll file unit of the type described, novel and improved means for retaining the tubular storage compartments in the frame of the unit.

A further object of the invention is to provide a roll file unit of the type described wherein the frame and the door of the unit cooperate in a novel and improved manner with opposite ends of the tubular storage compartments for retaining the latter in the frame.

Another object of the invention is to provide novel and improved means for detachably interconnecting a plurality of roll file units of the type described.

Other objects and advantages of the invention will become apparent from the subsequent detailed description taken in conjunction with the accompanying drawings, wherein:

FIG. 1 is a perspective view of an assembly of roll file units embodying the features of the present invention;

FIG. 2 is an enlarged vertical sectional view as taken substantially along the line 2—2 of FIG. 1 with intermediate portions broken away;

FIG. 3 is an enlarged vertical sectional view as taken substantially along the line 3—3 of FIG. 1 with intermediate portions broken away;

FIG. 4 is a fragmentary horizontal sectional view as taken along the line 4—4 of FIG. 3;

FIG. 5 is an enlarged plan view of a single roll file unit with intermediate portions broken away and with portions in section to reveal internal details of construction;

FIG. 6 is a vertical sectional view taken along the line 6—6 of FIG. 5;

FIG. 7 is a front elevational view of the unit shown in FIG. 5 as it would appear with the door of the unit in open position;

FIG. 8 is a fragmentary front elevational view of the unit shown in FIG. 5, the door being in closed position;

FIG. 9 is an enlarged fragmentary vertical sectional view as taken substantially along the line 9—9 of FIG. 5, the door being closed;

FIGS. 10 and 11 are views similar to FIG. 9 but showing the door in partially open and fully open positions, respectively; and

FIG. 12 is a fragmentary vertical section view taken along the line 12—12 of FIG. 6.

As shown in FIG. 1, the storage assembly comprises a plurality of individual roll file units A and B, each such unit having a relatively shallow rectangular or box-like configuration. The units A are interconnected in vertically stacked relation and the stack is connected laterally to

2

a similarly interconnected vertical stack of units B, as hereinafter described in detail. Each unit A and B comprises a rigid external frame or housing 21, preferably of metal, a plurality of internal tubular storage compartments 22 arranged in parallel side-by-side relation within the housing, and a hinged door 23 at the front of the unit.

The frame or housing 21 of each roll file unit comprises a pair of spaced parallel channels 24 (FIG. 2) having sidewalls 26 with top and bottom flanges 27 and 28, respectively, the channels 24 being rigidly connected at their opposite ends by front and rear cross members 29 and 31, respectively, to provide a rigid rectangular frame assembly which is open at its flat top and bottom sides (FIG. 5). The front cross member 29 includes a front panel 32 (FIG. 7) with inturned top, bottom, and side flanges 33, 34 and 36, respectively, the front panel 32 being provided with a plurality of openings 35 each aligned with an inwardly extending tubular flange 37 (FIGS. 9—11) for receiving the front ends of the tubular storage compartments 22. The rear cross member 31 has a rear panel 38 (FIG. 12) with inturned top, bottom, and side flanges 39, 41, and 42, respectively. The top flange 39 has a downturned marginal portion provided with slots 40 (FIG. 6) to form flange members 43 (FIGS. 6 and 12) which are inclined rearwardly, and the bottom flange 41 has an upturned marginal portion provided with similar slots to form flange members 44 also inclined rearwardly. The horizontal edges of the inclined flange members 43 and 44 are provided with complementary arcuate or scalloped upper and lower recesses 46 and 47 (FIG. 6), each pair of recesses 46—47 being aligned with one of the tubular flanges 37 at the front of the frame assembly and receiving the rear ends of the tubular storage compartments 22.

The compartments 22 consist of open-ended tubes, preferably of semi-rigid material such as heavy cardboard or fibrous material, and are of such length that when the tubes are inserted into the frame assembly through the openings 35 in the front panel 32, the rear ends of the tubes will abut the rear panel 38 while the front ends of the tubes are supported in the tubular flanges 37 but do not project substantially beyond the front panel 32. As will be clear from FIG. 12, during insertion of the tubes 22 from the front of the frame assembly, the rearwardly inclined flange members 43 and 44 flex slightly rearwardly and serve to guide or cam the rear ends of the tubes into proper position between the scalloped recesses 46—47, thereby facilitating installation of the tubes in the frame assembly. In addition, as shown in FIG. 6, the curvature of the scalloped recesses 46—47 is on a smaller radius and is non-concentric with respect to the curvature of the tubes 22 so that the periphery of each tube is engaged by the scalloped edges at essentially four circumferentially spaced points. This arrangement allows the spaced points of contact on the scalloped flanges to penetrate or dig in slightly into the outer surface of the semi-rigid tube material and, because of the rearward inclination of the flange members 43—44, tends to grip the tubes to resist withdrawal of the tubes, thereby effectively securing the tubes in assembled relation in the frame.

The door 23 at the front of each roll file unit comprises a main panel 51 (FIGS. 5, 7, and 8) with inwardly extending top, bottom, and side flanges 52, 53, and 54, respectively, the width and height of the door being slightly less than the corresponding dimensions of the front panel 32 of the frame assembly but large enough to enclose and conceal the openings 35 when the door is closed. The top flange 52 of the door 23 has a downturned marginal portion 55 (FIG. 9) adapted to abut the front wall 32 of the frame in flat engagement therewith when the door is closed. A card or label holder in the form of an elongated strip 56 (FIG. 8) is secured horizontally at the lower edge of the door panel 51 and has

inturned edges 57 for retaining a label 58 for identification of the contents of the file. As shown in FIGS. 9-11, the lower edge of the label holder projects slightly below the bottom edge of the door to serve as a finger grip for manipulating the door.

A pair of headed studs 61 (FIG. 5) are rigidly secured to the upper ends of the door side flanges 54 so that the inwardly projecting ends of the studs serve as hinge pins for pivotally mounting the door 23 on a pair of elongated generally L-shaped pivot links 62. The structure and operation of the hinge mechanism is best illustrated in FIGS. 9-11. As there shown, each pivot link 62 comprises a short upright arm portion 63, which is apertured at its outermost end to receive one of the hinge pins 61, and an elongated rearwardly extending arm portion 64. The arm portions 63 which support the door 23 are disposed forwardly of the front panel 32 of the frame, and the arm portions 64 extend rearwardly through a pair of slots 66 in the panel 32 and lie closely adjacent and parallel to the frame side walls 26 (FIG. 5). The arm portion 64 of each pivot link 62 has an offset shoulder 67 at its lower edge for abutting the inside of the front panel 32. The portion of the link extending through the slot 66 has relatively slight clearance from the edges of the slot, thereby retaining the lower shoulder 67 behind the panel 32 and preventing unintentional removal of the links 62 from the slots 66. The upper edge of each link 62, however, has an offset shoulder 65 which permits removal of the link through the slot 66 when the arm portions of the link are tilted downwardly. The innermost end of each arm portion 64 is slotted, as at 68, to provide a hook which is connected by a tension spring 69 to a loop 70 struck upwardly from the bottom flange 28 of the corresponding frame side member 24. A similar loop 71 (FIG. 6) is also provided on the top flange 27 so that the side walls 26 of the frame can be assembled to the front panel 32 with either edge up.

In assembling the door 23 on the frame, the apertured arms 13 of the pivot links 62 are first slipped onto the hinge pins 61 of the door. The arm portions 64 of the links are then inserted through the slots 66 in the front panel 32 and are rocked upwardly at their inner ends to allow the shoulders 67 to drop behind the panel 32 at the lower edges of the slots 66 and thereby allow the shoulders 65 to clear the upper edges of the slots 66, the dimensions of the slots being sufficient to permit such manipulation. Finally, the springs 69 are connected between the loops 70 and the inner hooked ends 68 of the pivot links to complete the assembly. To remove the door 23, the above-described sequence is carried out in reverse order, i.e. the springs 69 are first disconnected from the links, the inner ends of the links are rocked upwardly to allow passage of the shoulders 65 through the slots, and the links are then shifted upwardly to allow the shoulders 67 to pass through the slots for complete withdrawal of the links.

In the fully closed position of the door 23, as shown in FIG. 9, the tension of the springs 69 acting through the downwardly inclined links 62 holds the door firmly closed with the inner edges of the door flanges 52-53-54 and the inner surface of the marginal portion 55 engaging the front wall 32 of the frame. As will be apparent, the door is thus pivotally suspended on the upright arm portions 63 of the pivot links 62, and the links 62 have their lower edges, designated at 72, in engagement at 73 with the lower edges of the slots 66 for positioning the door in proper enclosing relation over the compartment openings 35. As will hereinafter appear, the points of engagement 73 constitute a fulcrum for the links 62, the fulcrum being at the innermost ends of the arm portions 63 below the pivots 61.

During initial opening movement of the door 23, the lower edge of the door swings outwardly and upwardly in an arc about the pivots 61. The inner horizontal corner of the door, designated at 74 in FIG. 10, at the juncture

between the top flange 52 and the marginal portion 55 is held by spring tension against the panel 32, and as the door 23 continues to open, the hinge pins 61 are displaced outwardly and the corner 74 slides downwardly along the panel 32. However, since the links 62 are prevented from moving outwardly by the shoulders 67, rocking movement of the links occurs so that the links pivot in a counterclockwise direction, as seen in FIGS. 9-11, about a fulcrum defined by the points of engagement 73 of the lower edges 72 of the links with the bottom edges of the slots 66. Thus, the pivots 61 are also displaced downwardly and outwardly until the FIG. 10 position is reached where the outer arms 63 are in their lowermost pivot position and the inner arms 64 are in their uppermost pivot position. Such movement increases the tension of the spring 69. To provide the required clearance for the arm portions 63 of the pivot links during swinging of the door, the marginal portion 55 on the door is notched at its ends, as indicated at 76 in FIG. 5.

As the door is moved beyond the FIG. 10 position toward the fully open position shown in FIG. 11, the springs 69 cause the door to continue such movement and the corner 74 to continue to slide downwardly along the front panel 32. When the door is fully open the top wall 52 is held by the springs 69 in firm flatwise engagement against the panel 32. During this latter part of the opening movement of the door, the pivot pins 61 move inwardly and upwardly to a final position intermediate their FIG. 9 and FIG. 10 positions. At the same time the links 62 pivot about their fulcrum points 73 in the opposite or clockwise direction until the arm portions 63 and 64 reach their FIG. 11 positions, intermediate the positions of FIG. 9 and FIG. 10, with the shoulders 67 still abutting the inside of the front panel 32 immediately below the lower edges of the slots 66.

To return the door to closed position, the reverse sequence is followed so that the parts shift from their FIG. 11 position to their FIG. 10 position with the links 62 rocking first in a counterclockwise direction. Finally, as the door moves from the FIG. 10 position to the FIG. 9 position, the links 62 pivot in a clockwise direction until the inner arm portions 64 are inclined downwardly in the manner shown in FIG. 9 with the lower corners of the shoulders 67 abutting the inside of the front panel 32.

Thus, it will be seen that the door is held in both closed and open positions by spring tension. The links 62 fulcrum solely about their pivot points 73 during both opening and closing of the door, and the link construction with the offset upper and lower shoulders 65 and 67 is such that unintentional detachment of the door from the frame is prevented but the parts are also readily detachable when desired for replacement or during initial assembly. As will readily be understood, the spring forces acting at an angle on the inner ends of the pivot arms 64 are amplified at the pivot pins 61 because of the different lengths of the pivot arms on opposite sides of fulcrum 73.

As previously pointed out, the storage compartment tubes 22 are held at their inner ends against withdrawal from the frame assembly by means of the rearwardly inclined scalloped flange members 43 and 44 while the front ends of the tubes are supported in the flanges 37 on the front panel 32. In addition, however, it will be seen from FIGS. 7 and 11 that the width of the top flange 52 on the door is such that when the door is fully open (FIG. 11) the lower edge of the flange 52 projects slightly below the upper parts of the openings 35 and overlies the outer axial ends of the tubes 22. Thus, inadvertent removal of the tubes 22 from the frame assembly is prevented by the combined action of the scalloped flanges 43-44 at the rear ends of the tubes and by the overlying door structure at the front ends of the tubes. This feature is particularly important when large or tightly wound rolled articles are stored in the tubes 22 and snugly engage the inner surfaces of the tubes. By the present arrangement there is

little likelihood of the tubes 22 being detached from the frame assembly during removal of such articles. Of course, it will be understood that during assembly of the storage device the tubes 22 must be mounted in the frame 21 before the door 23 is installed.

In FIG. 1, a plurality of roll file units A and B are shown in laterally and vertically interconnected relation. To hold a group of units in stacked relation, each rectangular frame 21 of an individual roll file unit is provided with cooperating pairs of projecting studs and elongated apertures or slots arranged in diagonally opposed relation at the top and bottom of the unit. Thus, as shown in FIGS. 1, 2, and 5, the top flange 33 of the front cross member 29 has an upstanding stud 81 at one end thereof and an aperture 82 at its opposite end. Similarly, the bottom flange 34 has a depending stud 83 aligned with the aperture 82 and an aperture 84 aligned with the stud 81. The top flange 39 and the bottom flange 41 of the rear cross member 31 are likewise provided with cooperating studs 81-83 and apertures 82-84 which are diagonally opposed to the studs 81-83 and the apertures 82-84 of the cross member 29.

As most clearly shown in FIG. 2, when one unit is stacked above the other, the diagonally opposed depending studs 83-83' of the upper unit are received in the apertures 82-82' of the lower unit and the diagonally opposed upright studs 81-81' of the lower unit are received in the apertures 84-84' of the upper unit thereby insuring proper orientation and stacked alignment of the units regardless of which side is uppermost.

For securing adjacent units together the channel members 29 of each frame 21 are provided with a plurality of elongated corner slots 91 and 92 (FIG. 1) located at the upper and lower junctures between the side panels 26 and the upper and lower flanges 27 and 28, respectively. When a pair of units are stacked vertically or disposed laterally adjacent each other, the slots 91-92 are brought into alignment either vertically or horizontally for co-operation with a plurality of U-shaped resilient clips 93 (FIGS. 3 and 4) each of which has a pair of resiliently spreadable legs 94 and 96 and a bight portion 97. As shown particularly in FIG. 3, when a pair of roll file units A or a pair of units B are stacked vertically, the upper corner slots 91 of the lowermost unit are vertically aligned with the lower corner slots 92 of the uppermost unit so as to receive the legs of a horizontally inserted clip 93 in each pair of aligned slots 91-92. Thus, the leg 94 of the clip 93 extends into the slot 92 and frictionally grips the flange 28 while the clip leg 96 extends into the slot 91 and frictionally grips the flange 27, the depth of the slots 92-91 inwardly of the flanges 28-27 being sufficient so that the bight portion 97 of the clip 93 is recessed inwardly from the outer surfaces of the side walls 26. For retaining the clips 93 in assembled relation on frames, each clip leg may be provided with suitable detent means such as a pair of apertures 98 in the respective legs adapted to snap into interlocking relation with complementary bulged projections or dimples 99 in the respective flanges 27-28.

In a similar manner, the clips 93 are also used in vertically disposed relation for laterally connecting the tops and the bottoms of a stack of units A with a stack of units B. Thus, as seen at the left-hand side of FIG. 3, a clip 93 has been inserted vertically downwardly so that its legs 94-96 extend into a pair of slots 91 of laterally adjacent units A and B and frictionally grip the parallel inside surfaces of the frame walls 26. The openings 98 in the clip legs may interlock with dimples 101 on the vertical walls 26 which are similar to the dimples 99 on the flanges 27-28. Although not shown in FIG. 3, it will be understood that a clip 93 may be similarly inserted vertically upwardly into a pair of juxtaposed slots 92 at the bottoms of the stacks of A and B units. Thus, the roll file units may be combined in modular fashion to provide

a storage assembly of any desired number of vertically and horizontally arranged units.

Although the invention has been described above with particular reference to certain specific structural embodiments, it is to be understood that various modifications and equivalents may be resorted to without departing from the scope of the invention as defined in the appended claims.

I claim:

- 10 1. In a roll storage means having a housing with front and rear end portions and a plurality of elongated storage tubes mounted in parallel relation in said housing between said end portions and having access openings at the front end portion of the housing, the improvement comprising support means at the rear end portion of said housing in gripping engagement with the outer peripheries of said tubes adjacent the rear ends thereof for resisting axial withdrawal of the tubes from the front end portion of the housing, and door structure hingedly supported at the front end portion of said housing for movement between open and closed positions, said door structure when in open position having a portion thereof partially overlying the front ends of said tubes thereby further preventing axial withdrawal of said tubes from the front end portion of said housing through said openings.
- 15 2. The structure of claim 1 further characterized in that said support means comprises rearwardly inclined flange means extending across said rear end portion of said housing transversely of said tubes, said flange means having arcuate edgewise recesses in which said tubes are disposed, the rearward inclination of said flange means permitting axial insertion of said tubes into said housing through said access openings but preventing axial withdrawal of said tubes through said openings.
- 20 3. The structure of claim 1 further characterized in that said support means comprises a pair of upper and lower rearwardly inclined flanges extending across the rear portion of said housing, said flanges having arcuate recessed edge portions engaging said tubes at opposite sides thereof.
- 25 4. Roll storage means comprising a housing with front and rear end portions, a plurality of elongated storage tubes disposed in parallel relation in said housing between said end portions, said front end portion providing access openings to the front ends of said tubes, support means at said front end portion of said housing for supporting the front ends of said tubes, and said rear end portion comprising a channel-shaped member with the web of the channel forming the rear wall of the housing, the flanges of the channel-shaped member extending forwardly and then bent toward each other and forming flange means extending transversely across the rear end of said housing and having edge portions engaging said tubes at the rear ends thereof for supporting the same and preventing axial withdrawal of said tubes through said openings.
- 30 5. The structure of claim 4 further characterized in that the bent portions of the flanges of the channel are notched to form a plurality of pairs of upper and lower flange members constituting said flange means, one pair of flange members for each tube, each pair of flange members being adapted to flex rearwardly on insertion of the tube therebetween and having edge portions gripping the tube to prevent forward withdrawal of the tube.
- 35 6. The structure of claim 5 further characterized in that each of said edge portions is provided with an arcuate recess of slightly smaller radius than and eccentric to the radius of the tube whereby each edge portion grips the tube at circumferentially spaced points.
- 40 7. The structure of claim 4 further characterized in that said pairs of upper and lower flanges are inclined toward the rear end portion of said housing and having opposed arcuate edge recesses in gripping engagement with said tubes.
- 45 8. The structure of claim 4 further characterized in that said support means comprises a plurality of tubular portions extending rearwardly from said openings.

9. A cabinet comprising a housing having a front wall with at least one access opening therein, a door having a front panel and a laterally extending flange along one edge of said panel, a pair of elongated pivot links extending through said wall in fulcruming engagement therewith, pivotal support means swingably supporting said door on said links adjacent the ends of said one edge and above the point of said fulcruming engagement and forwardly of said wall, and spring means interconnecting said links and said housing rearwardly of said wall, said flange extending laterally outwardly from said wall when said door is in closed position with said panel substantially parallel to said wall, said flange being disposed in flatwise contact with said wall when said door is in open position with said panel extending laterally outwardly from said wall, and said spring means resiliently holding said door in engagement with said wall at all times, said links being generally L-shaped with elongated arm portions extending rearwardly from said wall for connection with said spring means and relatively shorter arm portions extending transversely of said elongated arm portions forwardly of said wall for pivotally mounting said door, a pair of slots in said wall with said links extending through said slots, and said links having offset shoulder portions engageable with the rear side of said wall at the margins of said slots for retaining the links against forward movement.

10. A cabinet comprising a housing having a front wall with at least one access opening therein, a door disposed forwardly of said wall and having a front panel, a flange extending perpendicularly from one edge of said panel, and an inturned marginal portion on said flange extending parallel to said panel, the juncture between said flange and said marginal portion defining an inner corner on the door, said wall being provided with a pair of slots at opposite sides of the housing, a pair of generally L-shaped pivot links extending through said slots and having elongated arm portions extending rearwardly from said wall within said housing and relatively short arm portions extending angularly from said elongated arm portions and disposed forwardly of said wall, said links being in fulcruming engagement at the juncture of said long and short

5
10
15

25

arm portions with said wall at the edges of said slots, pivot means swingably mounting the door adjacent the outermost ends of said short arm portions for movement of the door between open and closed positions, and spring means interconnecting the inner ends of said elongated arm portions with said housing for resiliently holding the door against said wall in all positions of the door, said flange extending perpendicularly from said wall and said marginal portion being in flatwise contact with said wall when the door is in closed position overlying the open ends of said tubes, said panel and said marginal portion extending perpendicularly from said wall and said flange being in flatwise contact with said wall when the door is in open position, and said corner moving in sliding contact with said wall during opening and closing movements of the door, and the axis of said pivot means being displaced outwardly from said wall during sliding movement of said corner along said wall when the door is moved between open and closed positions thereby effecting rocking movement of said pivot links against the action of said spring means.

11. The structure of claim 10 further characterized in that said links have offset shoulder portions engageable with the rear side of said wall at the fulcruming edges of said slots for retaining the links against forward movement through the slots.
